US00D810065S

(12) **United States Design Patent** (10) **Patent No.:** **US D810,065 S**
(45) **Date of Patent:** **** Feb. 13, 2018**

(54) **PROTECTIVE COVER**

(71) Applicants: **Fu Tai Hua Industry (Shenzhen) Co., Ltd.**, Shenzhen (CN); **HON HAI PRECISION INDUSTRY CO., LTD.**, New Taipei (TW)

(72) Inventors: **Li-Wen Tien**, New Taipei (TW); **Lei Wang**, Shenzhen (CN); **Chang-Xue Lei**, Shenzhen (CN)

(73) Assignees: **Fu Tai Hua Industry (Shenzhen) Co., Ltd.**, Shenzhen (CN); **HON HAI PRECISION INDUSTRY CO., LTD.**, New Taipei (TW)

(**) Term: **15 Years**

(21) Appl. No.: **29/569,569**

(22) Filed: **Jun. 29, 2016**

(30) **Foreign Application Priority Data**

May 24, 2016 (CN) 2016 3 0199234

(51) **LOC (11) Cl.** **14-03**

(52) **U.S. Cl.**

USPC **D14/250**

(58) **Field of Classification Search**

USPC 455/575.8; D14/250

CPC A45C 2011/002; A45C 11/00

See application file for complete search history.

(57) **CLAIM**

We claim the ornamental design for a protective cover, as shown and described.

DESCRIPTION

FIG. 1 is a perspective view of a protective cover showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view showing the protective cover in use.

The broken lines are for illustrating unclaimed portions of the protective cover or environmental use; the broken lines form no part of the claimed design.

1 Claim, 8 Drawing Sheets
